CLAIM

The ornamental design for a basin faucet, as shown and described.

DESCRIPTION

FIG. 1 is a top, front, and right side perspective view of a basin faucet, showing the new design;

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof; and

FIG. 7 is a top view thereof;

FIG. 8 is a bottom view thereof; and,

FIG. 9 is a top, front and right side perspective view thereof shown in condition of use.

The broken lines in the drawings depict portions of the basin faucet that form no part of the claimed design.
